(57) **CLAIM**

We claim the ornamental design for a handle of a medical
tool, as shown and described.

DESCRIPTION

FIG. 1 is a perspective view of a handle of a medical tool
showing our new design.

FIG. 2 is a front view of our new design shown in FIG. 1.

FIG. 3 is a rear view of our new design shown in FIG. 1.

FIG. 4 is left-side view of our new design shown in FIG. 1.

FIG. 5 is a right-side view of our new design shown in FIG.

1.

FIG. 6 is a top view of our new design shown in FIG. 1; and,
FIG. 7 is a bottom view of our new design shown in FIG. 1.
The broken lines consisting of short broken lines show the
remaining portions of the handle of a medical tool that form
no part of the claimed design. The broken lines consisting of
dot-dash lines are boundary lines that show that the claimed
design extends to the boundary line but does not include the
boundary line.

The medical tool may be, but is not limited to, an orthopedic
tool, such as a broach, a reamer, or an impactor.
